UNITED STATES PATENT OFFICE

2,580,114

DRIVING MECHANISM FOR WALKING BEAM CONVEYERS

Stanley Marvin, Oakland, and William H. Orth, San Carlos, Calif.; said Orth assignor, by mesne assignments, to Peerco Corporation, San Francisco, Calif., a corporation of California, and said Marvin assignor, by mesne assignments, to Daco Metal Products, Oakland, Calif., a corporation of California

Application August 28, 1948, Serial No. 46,666

1 Claim. (Cl. 198—219)

1

This invention relates to a driving mechanism for a conveyor, and more particularly to such mechanism for a conveyor of the walking beam type.

Conveyors of the aforesaid type are well-known in the art, and may comprise a fixed table provided with a rail bed and a movable table provided with a rail bed, the rails of the latter intermeshing with the rails of the former, or the conveyor may comprise a pair of movable tables having intermeshing rail beds. In either case, the movement of the rails of one table in relation to the rails of the other describes an oval type path, the upper half of which is above the other rail-bed. Thus, articles placed on one of the rail beds are alternately transferred from one bed to the other, each transfer being made at a point farther along in the path of travel of the articles.

It is an object of the instant invention to provide an improved driving mechanism for a walking beam conveyor having fixed and movable rail beds.

A further object of the invention is to provide a novel, simple and efficient driving mechanism for a walking beam conveyor.

Briefly, the driving mechanism of the invention comprises a movable table mounted for travel on wheels carried by spaced pairs of rocker arms maintained in parallelism by interconnecting links. Cyclic movement of the rocker arms through the medium of a pitman arm connection between the rocker arms and an eccentric mounted on a driven shaft causes the movable table to rise and fall. Another pair of rocker arms, interconnected with eccentrics on the driven shaft by pitman arms, and having a lost motion connection with the movable table serves to impart an independent reciprocating motion to the latter in timed relation to the rising and falling of said table. Means are also provided to vary the amplitude of reciprocating movement of the table.

Further objects and advantages of the invention will be apparent from the following description taken in conjunction with the drawings forming part of this specification, and in which:

Figure 1 is a view in side elevation of a walking-beam conveyor embodying the driving mechanism forming the subject matter of the invention;

Figure 2 is a top plan view of the walking-beam conveyor;

Figure 3 is a view taken along lines 3—3 of Figure 2, showing in side elevation the arrangement of the lifting mechanism component of the driving mechanism of the conveyor;

2

Figure 4 is a view in end elevation of the structure of Figure 1, also showing an exhaust box type housing for the conveyor;

Figure 5 is an enlarged detail view of a portion of the lifting mechanism, taken along lines 5—5 of Figure 3; and

Figure 6 is an enlarged detail view of a portion of the driving mechanism, taken along lines 6—6 of Figure 1.

10 Referring to the drawings for more specific details of the invention, the conveyor has a fixed box-frame structure comprising lower support members 10 transversely interconnected by members 12, posts 14 carrying upper support members 16, and members 18 transversely interconnecting said upper support members 16. The transverse members 18 have secured thereto at spaced intervals clips 20 for the fixed support of rails 22.

The lower support members have secured 20 thereto at one end flanged plates 24, said plates have mounted thereon bearing yokes 26 supporting a shaft 28 for rotation. The shaft 28 has secured thereto a driving gear 30, a pair of eccentrics 32 having flanges 34, and another pair of 25 eccentrics 36 having flanges 38. Each of the eccentrics 36 is provided with a pitman arm 40 secured thereto by a strap 42, said arms 40 being provided with yoke ends 44 receiving therebetween the ends of parallel links 46. The ends 44 of the pitman arms, and the ends of the parallel links 46, together with flanged wheels 48 are pivotally mounted on bolts 50 secured by nuts 51 through yoke arms 52 of rocker arms 54 secured to a rocker shaft 56 journalled in bearing members 58 secured to the lower support members 10. 30 The parallel links are pivotally secured at spaced intervals between yoke ends 60 of rocker arms 62 by bolts 64 and nuts 66, said rocker arms being secured to rocker shafts 68 journalled in bearing members 70 secured to the supports 10. Each of 35 the bolts 64 pivotally supports a flanged wheel 72. 40

The conveyor is provided with a movable frame comprising spaced horizontal beams or support members 74 transversely interconnected by beams 76 having secured thereto a plurality of spaced 45 connectors 78, supporting a plurality of rails 80 alternately arranged with respect to the fixed rails 22 of the fixed frame portion of the conveyor. The support members 74 have affixed thereto and dependent therefrom a plurality of 50 shoes 82 having rail ends 84 supported on the wheels 48 and 62 between the flanges of said wheels. Thus, the rocker arms 54 and 62, maintained in mutual parallelism by the parallel links 55 46 support the movable frame structure of the conveyor, and do so in such manner that when

the rocker arms are vertical, as shown in the right hand portion of Figure 3, the rails 80 carried by the movable frame are raised to project above the fixed rails 22, while the upper edges of the rails 80 are lowered beneath the upper edges of the fixed rails 22 when the rocker arms are substantially inclined from the vertical, as shown in the left hand portion of Figure 3, the amplitude of the rocker arms being limited by the throw of the pitman arms 40 and eccentrics 34.

The movable frame is prevented from endwise displacement from the wheels 48 and 72, and is also adapted for reciprocal movement by the following mechanism: The middle pair of shoes 82 is provided with outwardly extending rollers 86 extending between spaced ribs 88 on the inner side of the upper end of rocker arms 90 pivotally carried on the outer ends of rocker shaft 68. The rocker arms 90 are provided with longitudinal slots 92 in which flanged pivot studs 94 are selectively positionable in accordance with suitable indicia on scales 96 adjacent the slots, said studs being adapted to be secured to the end of pitman arms 98 by nuts 100. The nuts 100 secure the studs 94 and the ends of the pitman arms 98 to the rocker arms 90 in any desired position in the slots 92. The opposite ends of the pitman arms 98 are secured as by pins 102 to bearing straps 104 comprising yokes 106 and 108 having their ends secured together and in engagement with the eccentrics 32 between the flanges 34 thereof.

The eccentrics 32 and 36 are preferably, though not necessarily, of the same size and are so arranged with respect to each other that upon the rotation of shaft 28 in a clockwise direction, as viewed in Figures 1 and 3, caused by suitable driving means, not shown, in engagement with a chain drive 110 passing over the gear 30 on shaft 28, the rocker arms 54 and 62 move from the inclined position shown at the left side of Figure 3 to the vertical position shown at the right side of Figure 3, and back to the inclined position, during one complete revolution of the shaft 28. Meanwhile, the rocker arms 90 move from a position wherein they are inclined to the left of a vertical position to a position wherein they are inclined to the right of the vertical, and back again, during one complete revolution of the shaft 28. The resultant movement imparted to the rails 80 causes them to travel more upwardly than forwardly in the first stage of the cycle, until the rails 80 rise above the rails 22, this being due to a certain degree of lost motion between the rollers 86 of the shoes 82 and the ribs 88 of the rocker arms 90 when the direction of movement of the latter is reversed; upwardly to a maximum degree and forwardly to a maximum degree; more downwardly than rearwardly until the rails 80 dip below the rails 22, also due to the lost motion between the rollers 86 and the ribs 88 when the rocker arms reverse their direction; and downwardly to a maximum degree and rearwardly to a maximum degree to complete the full cycle. During the cycle of travel, the driving connection between the rollers 86 and ribs 88 does not hinder the vertical movement of the rails 80, and the vertical movement of the rollers 86 is not sufficient to bring said rollers out of engagement with the ribs 88.

The amplitude of reciprocatory movement of the movable frame may be varied by changing the points of connection between the ends of the pitman arms 98 and the rocker arms 90 within the slots 92. Thus, if the arms 98 are connected to the rocker arms at the lower end of the slots, the amplitude of the movable frame will be at a maximum, while if the connection is made at the upper ends of the slots the amplitude will be at a minimum.

It will be seen from the foregoing description of the driving mechanism of the invention and the operation thereof that we have provided a novel, simple and efficient arrangement for the imparting of motion to the movable frame portion of a walking beam type conveyor.

While the preferred embodiment of the invention has been shown and described, it will be understood that the embodiment set forth is susceptible of change within the spirit of the invention and the scope of the appended claim.

What we claim as new and desire to secure by Letters Patent is:

In combination, a fixed frame having a plurality of parallel spaced supporting elements, a movable frame having a plurality of parallel spaced supporting elements, and driving means for imparting a compound motion to said movable frame to cause the supporting elements thereof to travel a cyclic path above and forwardly and below and rearwardly of the supporting elements of the fixed frame; said driving means comprising a plurality of pairs of pivotally mounted arms, links interconnecting said pairs of arms to maintain them in parallelism, rollers carried by said arms adjacent the upper ends thereof for the support of said movable frame, a driven shaft, a first pair of eccentrics mounted on said shaft for rotation therewith, pitman arms mounted on the peripheries of said eccentrics and each connected to one of said links adapted to rock said pivotally mounted arms from an inclined position to a substantially vertical position and back to said inclined position upon a complete rotation of said shaft, another pair of pivotally mounted arms, another pair of eccentrics mounted on said shaft for rotation therewith, other pitman arms mounted on the peripheries of said eccentrics, slots in said other pair of arms for connecting said other pair of pitman arms thereto at various distances from the pivotal axis of said arms, and a slidable lost motion connection between said slotted arms and said movable frame adapted to impart a horizontal component of motion to said frame upon the rocking motion of said slotted arms.
